UNITED STATES PATENT OFFICE

GARVEY E. LYONS, OF ST. LOUIS, MISSOURI, AND BERT J. ANDERSON, OF HAMMOND, INDIANA, ASSIGNEES TO THE METALCRAFT CORPORATION, OF ST. LOUIS, MISSOURI, A CORPORATION OF MISSOURI

STRUCTURAL TOY

Application filed July 24, 1929. Serial No. 380,533.

This invention relates to new and useful improvements in structural toys and more particularly in toy railroad cars.

The objects of the invention are to provide a structural toy consisting of a wheeled body and a plurality of interchangeable parts whereby various types of cars can be built by the use of appropriate parts.

Further objects of the invention are to provide a structural toy car having a wheeled base or body portion and a plurality of interchangeable parts adapted to be detachably secured in assembled relation on said body portion.

Other objects of the invention are to provide a structural toy car comprising a body portion and car trucks detachably secured thereto, said trucks having pivotal engagement with said body portion to permit swinging movement of the latter relative to said trucks, the wheels of the truck being carried by axles which are detachably arranged in the sides of said trucks and are interchangeable so as to adjust said wheels to tracks of different widths or gauges.

Additional objects of the invention are to provide a construction set comprising a plurality of interchangeable metallic parts whereby a wheeled toy, such as a railroad car, can be built to represent various types of cars.

With these and other objects in view, our invention consists in certain novel features of construction and arrangement of parts, hereinafter more fully described and claimed, and illustrated in the accompanying drawings, in which—

Figure 1 is a side elevational view of a flat car.

Figure 2 is a top plan view of same, partly broken away.

Figure 3 is an end elevational view of same.

Figure 4 is an end elevational view of a modified form.

Figure 5 is an enlarged cross sectional detail view taken on line 5—5 of Figure 2.

Figure 6 is an enlarged detail view taken on line 6—6 of Figure 1.

Figure 7 is a side elevational view of a stake car.

Figure 8 is a top plan view of same.

Figure 9 is an enlarged detail view taken on line 9—9 of Figure 8.

Figure 10 is a side elevational view of a tank car with the car trucks partly broken away.

Figure 11 is a cross section taken on line 11—11 of Figure 10.

Figure 12 is a side elevational view of a box car.

Figure 13 is an end elevational view of same partly in cross section.

Figure 14 is a front elevational view of one of the car end sections.

Figure 15 is a vertical cross section taken on line 15—15 of Figure 12.

Figure 16 is a side elevational view of a stock car with the car trucks partly broken away.

Figure 17 is a side elevational view of a derrick car with the car trucks broken away.

Figure 18 is an end elevational view of same.

Figure 19 is a side elevational view, partly broken away, of a passenger car.

Figure 20 is an end elevational view of same.

Figure 21 is a side elevational view of a caboose car.

Figure 22 is an end elevational view of same.

Figure 23 is a cross section of same, taken on line 23—23 of Figure 21.

Figure 24 is a side elevational view partly broken away of a gondola car.

Figure 25 is a side elevational view of a hopper car.

Figure 26 is a cross section of same taken on line 26—26 of Figure 25.

Figure 27 is a side elevational view of an armoured car, partly broken away.

Figure 28 is a cross section taken on line 28—28 of Figure 27.

The purpose of the present invention is the provision of a construction set whereby toy railroad cars of various types can be built by the use of different parts furnished with the set, the car trucks and the base portion being used without change in conjunction with all the different types of cars. The vari-

ous parts utilized to form the different bodies of the cars are standardized so that they can be used interchangeably with the base, the parts being secured preferably by means of suitable nuts and bolts.

Referring by numerals to the accompanying drawings, 10 indicates a flat car consisting of a pair of wheeled trucks 11 and a car base member 12. The latter is preferably secured to each truck by means of a bolt 13 which extends downwardly through a sleeve 14 formed integral with and depending from the horizontal portion 15 of base member 12. A washer 16 is arranged against the lower end of sleeve 14 and bearing against said washer is a nut 17 which is screwed on the threaded end of bolt 13.

Each truck 11 comprises a horizontal portion 18 which is arranged against the underside of member 15 and is provided with a central aperture 19 in which is operatively disposed sleeve 14 so that each truck 11 and base 12 can swing on the axis of each bolt 13 in a horizontal plane independently of each other. Each truck 11 is provided with side pieces 20 which are formed integral with member 18 and extend downwardly to each side thereof and are shaped so as to represent journal boxes 21. Journal box portions 21 are apertured for the reception of ends of an axle 23 which extend therethrough and are each secured thereagainst preferably by a securing nut 24 and a locking nut 25 which are screwed on the threaded ends of said axle. A car wheel 26 is loosely arranged on each axle adjacent to each journal box portion 21.

In the preferred form the car wheels 26 are arranged on the inside of said journal box portions and are held against inward movement by nuts 27 and locking nuts 28.

With the wheels arranged on the inside of the car truck, the car is designed for use on narrow gauge tracks. When it is desired to use the car on the standard gauge track, the car wheels are arranged on the outside of the car truck as shown in the modified form in Figure 4.

In this form an axle 29 is provided at one end with a head 30 and one of the car wheels 31 is arranged between this head and the outer face of the corresponding journal box portion 21. The other end of the car axle is provided with an aperture in which is adapted to be arranged a cotter pin 31. A washer 32 is preferably arranged between said cotter pin and the corresponding car wheel 26. The distance between each pair of wheels when thus assembled corresponds to the standard gauge track used with the various toy trains.

Each base member 12 is provided with longitudinally disposed flanges 15^a which are preferably turned upwardly. Each of these flanges is formed with a series of spaced apertures 34 which serve to receive means for attaching the various parts in building dif-

ferent types of car bodies. Portion 15 is provided with a vertically disposed aperture 35 which is arranged equidistant from the ends of member 12 on the longitudinal axis thereof and substantially in line with sleeves 14. Each end of member 15 is provided with a series of apertures 36 suitably spaced apart.

When it is desired to build a stake car, such as shown in Figure 7, stakes 37 which are provided for the purpose are attached to flanges 15^a by means of bolts and nuts 38 and 39, respectively, which pass through the apertures formed in the lower ends of said stakes and through the apertures 34 formed in flanges 15^a. Stakes 37 are preferably formed channel-shape in cross section but may be of other shapes if so desired. In the present instance, the flanges of each stake are cut away near the lower end thereof as indicated at 40 so that when the stake is in position the lower ends of the flanges rest on the upwardly presented edge of flange 15^a.

When it is desired to build a tank car (Figures 10 and 11), a tank 41 is attached to the flat car, such as shown in Figure 1, by means of a bolt 42 and nut 43. The bolt is passed through an aperture 41^a formed in the peripheral wall of the tank and through aperture 35, and is secured in position by nut 43. The tank 41 consists of an open ended cylinder 44, the length of which is slightly less than the length of member 12 and said cylinder is of suitable diameter so as to preserve the general proportions. The ends of this member are closed by caps 45 which are secured thereto by an elongated screw or rod 46 which passes through central apertures formed in said caps and extends longitudinally through member 41. The threaded end of the rod 46 receives a suitable nut which when tightened secures caps 45 in position on the ends of member 41.

The peripheral wall of member 41 is provided at a point diametrically opposed to bolt 42 with an aperture 47 through which is passed the threaded end of a bolt 48. The head of this bolt bears against a cap 49 of a dome member 50 which latter fits against the upper face of member 41. Cap 49 and dome 50 are secured in position by bolt 48 and a nut 51 which is screwed on the threaded end of said bolt and bears against the underside of member 41. Preferably this member is provided with a pair of spaced apertures 52 which are arranged in line with the aperture receiving bolt 42 and are so spaced as to be arranged in axial alignment with bolts 13 of the car structure 10. Thus said apertures 52 not only provide the necessary clearance for the heads of said bolts but also serve to hold the cylindrical member 41 against turning on the axis of bolt 42.

In Figures 12 to 15 is shown a box car construction. In this form a series of side wall members 54 is secured at their lower edges 130

to the flanges 15^a, preferably by the same screw bolt and nut fastening means 38 and 39 which are used to attach stakes 37 in position. Members 54 are spaced from each other to provide a door opening 55 which is closed by a sliding door 56. The sliding door is arranged on the inside of members 54 and a short section 57 is preferably secured to flange 15^a between sections 54. Side wall members 54 are provided at their upper edges with ears 56 to which is secured by suitable bolt and nut fastening means 57 a roof 58. The ends of the box car are closed by end wall sections 59 each of which is provided with a series of inwardly extending ears 60 which are adapted to be secured by bolt and nut means 61 to the end edges of members 54.

The sliding door 56 is preferably disposed in vertical plane with each flange 15^a and has the lower edge resting on the upwardly presented edge of the flange. Each door is held in position by a guide 62 which is arranged against the inner side of the flange and is substantially coextensive with the extent of movement of the door. The upper edge of this guide extends a suitable distance above the lower edge of the door, thereby preventing the door from jumping off its support. A similar guide 63 is arranged to guide the upper edge of the door and this guide is secured in position by the attaching means 57 used to attach the roof 58 in position while guide 62 is secured in position by attaching means 38 and 39, used to secure side wall members 54 and members 57 in position against flanges 15^a.

The stock car shown in Figure 16 is constructed in a manner similar to the box car with the exception that the side wall members 64 are provided with a series of elongated openings 65 and the sliding door 66 is also provided with a series of elongated openings 67 so as to give the appearance that said side members and said doors are constructed of a series of horizontally disposed spaced rails. Both sliding doors 56 and 66 are provided at a suitable height and near their outer edges with screws 68, the heads of which are presented outwardly and form handles by means of which said doors can be operated. Also said heads form stops for limiting the closing movement of said door.

In the form shown in Figures 17 and 18, a derrick car is illustrated. In this form a platform member 69 of inverted U-shape cross section is secured at its longitudinal flanges to the flanges 15^a by bolts and nuts 38 and 39. A crane housing 70 is secured to this platform by a bolt and screw attaching means 71 which is arranged centrally of said housing and of said platform so that the derrick can be moved about the vertical axis of said means 71. This housing 70 comprises a bottom member 72 which rests on platform 69 and is secured thereto by the aforesaid

fastening means 71. The longitudinal edges of this bottom member 72 are turned upwardly and have attached thereto the lower edges of side walls 73, the upper edges of which carry a roof 74 having a smoke stack extension 75. A derrick 76 consists of two spaced members, the lower ends of which are attached, by means 77, to the respective side walls 73. These members extend diagonally from the housing and have their upper ends extended horizontally and provided with a pair of sheaves 78 over which operates a cable 79. One end of the cable is provided with a hook 80 and the other end of the cable extends into the housing and is wound on the horizontally disposed shaft 81 which is mounted in the walls 73 and has one end provided with a handle 82 by means of which said cable can be operated to raise and lower hook 80. The housing 70 carrying derrick 76 can be moved about the vertical axis of member 71 so as to bring said derrick and hook 80 at any angle to the central vertical axis of the car.

In the form shown in Figures 19 and 20, a passenger car is illustrated comprising side wall members 83, the lower edges of which are secured to flanges 15^a by attaching means 38 while the upper edges receive a roof 84. This roof is given the proper shape so as to imitate the roof of the passenger cars and the side wall members 83 are provided with suitable windows 85. The ends of the passenger cars are closed by suitable end walls 86 having door openings 87. Doors 88 are formed in the side wall members 84. Steps 89 are provided for each side door 88.

The caboose car (Figures 21 and 23) is built by means of side wall members 90 which are attached to flanges 15^a and carry the roof member 58. End wall sections 59 are detachably attached to the side wall sections 90 to complete the caboose. The side wall members 90 are comparatively shorter than the member 12, thereby providing at each end of the caboose platforms 91.

Rail sections 92 are detachably secured to the ends of member 12, preferably by suitable fastening means engaging the apertures 36 and steps 89 are attached to flanges 15^a and lead to said platforms 91. One of the platforms is provided with a brake wheel 94 which is secured to the upper end of a vertically disposed rod 95. This rod has a bearing in a bracket 96 attached to one of the end rail sections 92 and the lower end of said rod passes through the central aperture 36 and is secured by a suitable nut in position in member 15. This brake wheel arrangement is also used in connection with the box car (see Figure 15) and stock car (see Figure 16) wherein a longer rod 95^a is used and the bracket 96 is attached to one of the end sections 59 and receives the lower end of the rod, while the upper end of the

rod passes through an aperture formed in the overhanging portion of roof 58. Rod 95 is secured in position by suitable nuts 97.

5 A cupola 98 is secured to roof 58 and projects upwardly therefrom. This cupola comprises a wall member 99 and a roof 100 and is held in position on roof 58 by a bolt 101, the head of which rests against roof 100 while the bolt passes downwardly through an aperture formed in roof 58 and receives a nut 102 which bears against the underside of said roof and holds said cupola in position.

10 In Figure 24 is shown a gondola car having side wall members 103 detachably attached to flanges 15^a and having end wall sections 104 detachably attached to the ends of side wall sections 103 while the top of the car is open.

15 A hopper car 105 is shown in Figures 25 and 26. This hopper car comprises side wall members 106, the parallel horizontal edges of which are provided with a series of spaced apertures 107 which are arranged in the upper edge and apertures 108 which are arranged in the lower edge. These apertures are so arranged that they are adapted to coincide with the apertures 34 formed in flanges 15^a. The same fastening means 38 and 39 are used to attach side walls 106 in position 20 on member 12.

25 The end edges of side walls 106 extend vertically for a short distance from the upper edges and are then inclined inwardly and downwardly so as to produce the hopper effect. End walls 109 are similarly shaped and are provided with a series of apertured ears 110 which coincide with apertures formed in said side walls whereby the end walls can be attached in position thereto by 30 suitable fastening means 112. To carry out further the hopper effect, a section 114 is secured to the underside of bottom wall 15 by a bolt and nut 115 which engages aperture 35 formed in bottom wall 15. The end 35 walls of this member 114 are disposed obliquely as indicated at 114^a. The side walls 106 are preferably disposed on the outside of flanges 15^a and in order to provide clearance for said flanges each end wall section 109 is provided in each corner with a notch 116 adapted to accommodate said flanges.

40 In building an armoured car, such as shown in Figures 27 and 28, member 114 is dispensed with and the upper structure comprising the hopper is placed on member 12 in inverted position with apertures 107 aligned with apertures 34, the same fastening means 38 and 39 being used to secure the body member in position. The end walls 109 are now inclined upwardly and inwardly. The member 69 used for mounting the derrick housing 73 is attached in position 45 between the upper edges of the side wall members 106 and forms a mounting for an assemblage 117 which represents a machine-

gun. This assemblage comprises a turret member 118 having upwardly extending flanges suitably apertured and arranged in one of these apertures is comparatively long screw 119 which extends radially therefrom and represents a machine-gun. Member 118 is provided in its bottom with a central aperture through which passes the bolt of suitable fastening means 120 by means of which the assemblage 118 is secured to member 69. Assemblage 117 can be moved about the vertical axis of fastening means 120 so that the machine-gun 119 can be placed at any angle on the car structure.

50 Thus it will be seen that various types of cars can be built from each construction set. A suitable coupler (not shown) can be attached to the central opening 36 of each member 12 whereby a number of cars can be coupled together. The parts can be colored or finished with any non-rusting process. As the only fastening means employed in the set consists of bolts and nuts, the parts can be easily assembled, without requiring a great degree of skill.

55 The great variety of models, provided by the construction set, enhances the usefulness thereof, as a child can readily build other models when tired of one type of car.

60 As the parts are all made of metal, they are not likely to be damaged and will withstand considerable amount of abuse. Further, such parts can be manufactured economically, as they can be stamped.

65 We claim:

1. A structural toy railroad car comprising in combination a flat car body open at both ends and having its sides formed with longitudinally disposed flanges, a car truck frame pivotally connected to said car body near each end thereof, a pair of axles detachably journaled in each car truck, a pair of car wheels detachably mounted on each axle, and detachable means on each axle for securing said wheels thereon and securing said axle in said car truck.

70 2. A structural toy railroad car of the class described comprising in combination a flat car body open at both ends and having its sides formed with longitudinally disposed flanges, each of which is provided with a plurality of spaced apertures adapted to receive suitable attaching means whereby various car body structures can be attached to said flat car body, a car truck frame having integral side members, a bolt for pivotally attaching said car truck to said car body near each end thereof, a pair of axles mounted in said side members of each car truck, a pair of wheels arranged on each axle, and means for securing said axles in said side members and said wheels on said axles.

75 3. In a structural toy railroad car, the combination of a flat car body open at both ends and having its sides provided with in-

tegral longitudinally disposed flanges, each of which is provided with a plurality of spaced apertures, a car body structure adapted to be placed on said flat car body,
5 bolts for engaging said car body structure and said apertures in said side flanges for detachably securing said parts together, a pair of car truck frames, a bolt for detachably and pivotally engaging each car truck
10 to said flat car body near each end thereof, a pair of axles detachably mounted in each car truck, a pair of car wheels arranged on each axle, and nuts screw-threaded on the ends of each axle for securing said car
15 wheels in spaced relation with each other and with said car truck and maintaining said axles in position.

In testimony whereof we hereunto affix our signatures this 8th day of July, 1929.
